UNITED STATES PATENT OFFICE

2,032,839

STALL CONSTRUCTION

Robert G. Ferris, Harvard, Ill., assignor to Star-line, Inc., Harvard, Ill., a corporation of Illinois

Application June 2, 1934, Serial No. 728,778

18-Claims. (Cl. 119—27)

My invention relates more particularly to stall constructions in which the curbs commonly of concrete and located between the stalls proper and the mangers, support the stall fronts, at curb engaging members associated therewith and adapted to be applied to the preformed curbs.

One of my objects is to provide an improved means for anchoring the stall fronts to the curbs which will be particularly adapted for use on curbs the front and rear faces of which converge upwardly.

Referring to the accompanying drawings:

Figure 1 is a perspective sectional view, showing a series of stalls embodying my invention.

Figure 2 is a face view of a portion of one of the similar stall constructions of Fig. 1.

Figure 3 is an enlarged broken longitudinal sectional view, in elevation, of the structure of Fig. 2 showing a detail of one of the similar stall-front anchoring means, the section being taken at the line 3 on Fig. 5 and viewed in the direction of the arrow.

Figure 4 is an enlarged sectional view taken at the line 4 on Fig. 2 and viewed in the direction of the arrow.

Figure 5 is an enlarged broken sectional view taken at the line 5 on Fig. 2 and viewed in the direction of the arrow.

Figure 6 is an enlarged broken sectional view taken at the line 6 on Fig. 2 and viewed in the direction of the arrow.

Figure 7 is a view in elevation of a modification of the stall front securing means of the preceding figures.

Figure 8 is a section taken at the line 8 on Fig. 7 and viewed in the direction of the arrow.

Figure 9 is a view like Fig. 7 of another modification of the securing means.

Figure 10 is a section taken at the line 10 on Fig. 9 and viewed in the direction of the arrow.

Figure 11 is a cross sectional view showing still another modification of the invention; and

Figure 12 is a fragmentary sectional view showing a modification of the structure of Fig. 11.

As a premise to the following description it may be stated that my improved securing means are of such obstruction that they exert compression forces against the curb not only substantially vertically but also horizontally, resulting in the rigid securing of the stall fronts to the curb with the minimum manipulation of parts.

Referring to Figs. 1 to 6, inclusive, of the drawings, 12 represents the curb of a stall construction and on which the stall fronts, represented at 13, and arranged in a series along the curb,

are supported, the stall fronts being connected together by cross members 13^a from which the side members 13^b of the stalls rearwardly extend, and the curb 12 being shown as of upwardly tapering form in cross section. The stall fronts 13 in accordance with common practice are each formed of a frame presenting a top cross bar 13^c and depending side bars 14 connected therewith, and a stanchion 15 mounted in the frame.

Surrounding the lower ends of the frame-sides 10 14 are heads 16 shown as of channel form presenting side flanges 17 extending along the top of the curb, the heads 16 containing apertures 18 between their ends surrounded by upwardly extending ring flanges 19 at which the heads 16 15 fit over the frame-sides 14.

The frame-sides are provided with cross pins 20 the ends of which extend into grooves 21 in the channel sides of the heads 16 and opening downwardly through the heads, the frame-sides 20 being held down to the curb by the engagement of the upper end walls 22 of the grooves 21, with the ends of the pins 20.

The heads 16 are also provided at opposite sides with depending ears 23 at which the heads straddle the upper portion of the curb as shown.

The construction illustrated is of the type in which bars, shown as of channel form and represented at 24, and extending between adjacent frame-sides 14, present pivoting means represented generally at 25 for the lower ends of the rotatable stanchion 15, these bars being telescoped at their ends with the channeled ends of the heads 16 as shown and having perforations 26 alining with depending projections 27 on the 35 ends of the heads 16, these projections being shown as formed by striking down the metal of the heads at these points whereby set screw-receiving-recesses 28 on the upper faces of the heads are provided.

Located at opposite sides of the frame-sides 14 and straddling the channel ends of the heads 16 are clamps represented at 29, these clamps, which are made of springy metal, as for example and preferably of semi-spring drop-forged steel, presenting upper cross portions 30 from which extend downwardly diverging arms 31 having inwardly extending projections 32 at their lower ends which extend into openings 33 in the opposite faces of the curb and at which arms the 50 clamps straddle the ends of the heads 16 and the curb as shown.

The clamps 29 also comprise set screws 34 threaded in the cross bars 30 thereof and engaging the ends of the heads 16 at the recesses 28, 55

As will be understood the tightening of the set screws 34 causes the clamps 29, heads 16, frame-sides 14, bars 24 and curb, to become rigidly secured together. The force directed upwardly 5 against the cross pieces 30 of the clamps by the screws 34 being applied to the clamps between the areas at which the projections 32 bear upwardly against the walls of the openings 33, the arms 31 of the clamps deflect inwardly against 10 the curb causing the material of the latter to be placed under compression not only substantially vertically but also horizontally.

The arms 31 being springy the clamps may be readily applied to the curb to the position shown 15 in which the projections 32 enter the openings 33, by sliding the clamp in curb-straddling position down the inclined walls of the curb, the arms 31 yielding outwardly until the projections 32 reach the openings 33 whereupon these arms spring inwardly and enter the projections in the openings. 20 In practice it would be desirable, though not necessary, to provide the clamps with their arms diverging at such an angle in the normal condition of the clamps, that the arms would be spaced 25 apart a slightly less distance than when seated to final position on the curb and thus the arms themselves, independent of the adjusting screws, exert a hugging action against the curb.

The arms 31, in effect, are swingably supported 30 and thus if modified to be provided as separate parts pivoted, or hinged, together would function generally as in the case of the construction of Figs. 1-6.

The securing means in Figs. 7 and 8 comprise 35 a channeled head represented at 35 surrounding the lower end of the frame-sides 14 with a pin connection (not shown) between these parts as in the case of the construction of the previous figures, the channeled ends of the head 35 straddling the adjacent bars 24 seated on the curb 12.

The clamp means of this construction comprises a yoke shaped member 36 of non-springy metal which straddles the upwardly extending tubular extension 37 of the head 35 and bears 40 against a stop surface 38 on the extension 37. The lower ends of the arms 39 of the yoke 36, which are preferably bent between their ends to extend substantially parallel with the inclined faces of the curb 12, are provided with inwardly 45 extending projections 40^a which extend into openings 41 in one face of the curb. The clamp also comprises a rod 42 of non-springy metal which extends at its upper portion loosely through an opening in the head 37 and carries 50 a nut 43 at its upper threaded end. The lower end of the rod 42 which is slightly deflected downwardly as shown is provided with an inwardly extending projection 44 which extends into an opening 44^a in the face of the curb opposite that 55 containing the openings 41.

The parts of this construction are preferably so proportioned that when the yoke 36 is applied to position on the head 37 with its projections 40 extending into the openings 41, but before the 60 nut 43 is tightened, the frame structure will be slightly displaced to the left in Fig. 8 from the position therein shown. Thus when the nut 43 is tightened the parts shown will shift to the centralized position shown in Fig. 8 in which operation 65 the arms 39 and rod 42 tend to swing toward each other and thus the compressive forces applied by the clamp to the curb are exerted not only substantially vertically but also horizontally; placing the material of the curb in compression as 70 described of the construction shown in Figs. 1-6.

The securing means shown in Figs. 9 and 10 comprise a pair of intersecting yoke members 46 and 47 each of non-springy metal and of substantially the same form as the yoke 39 of Figs. 7 and 8, these yoke members engaging stop surfaces 48 and 49, respectively, located at opposite sides of a head 53 associated with the lower end of the frame-side 14 as explained of the head 35. The lower portions of the yokes 46 and 47 diverge downwardly and the lower ends of the arms of 10 each thereof are provided with tensioning means shown as in the form of set screws 51 which are threaded in the arms and incline upwardly and inwardly in openings 52 in the opposite faces of the curb 12 and against walls 52^a of which the 15 set screws bear. Upon tightening the screws 51 against the bottom walls of the openings 52 the material of the curb is subjected to compression stresses not only substantially vertically but also horizontally, as in the previously described constructions.

The securing means shown in Fig. 11 comprise a head represented at 53 and associated with the frame-side 14 as explained of the constructions of the preceding figures, this head being provided 20 with ears 54 apertured to receive the upper threaded ends of rods 55 of springy metal which diverge downwardly and are provided at their lower ends with inwardly extending projections 56 which extend into openings 57 in the faces 30 of the curb 12. The upper ends of the rods 55 carry nuts 58 which when both are placed under tension by tightening them, operate to exert force on the rods 55 tending to raise them and swing them inwardly thus placing the material of the 35 curb under compressive stresses not only substantially vertically but also horizontally.

The rods 55 may be made of rigid, non-springy, material, in which case it is necessary that they be free to swing inwardly at their points of support on the head 53. Thus the openings in the head through which the rods extend may be downwardly flaring as represented at 59 in Fig. 12.

In the particular constructions shown in Figs. 1 to 8, inclusive, and 11 and 12, the gripping of 45 the curb horizontally is at side walls of the arms of the clamps. It will be understood, however, that instead of providing for the horizontal gripping of the curb as stated, such gripping may be effected by engagement of the inner end faces 50 of the projection on the clamp arms with the end walls of the openings into which they extend, these end faces and end walls of the several constructions shown being represented at 32^a, 40^a, 44^a, 56^a, and 33^a, 41^a, 45^a and 57^a, in which cases 55 the parts would be so proportioned that the side surfaces of the clamp arms would be spaced from the side walls of the curb. It is desirable that the points of engagement of the clamps with the heads of the frame-sides be as low as possible 60 on the frame-sides and still engage the projections on the clamp arms with the curb at such an elevation below the top of the curb as to prevent stripping of the curb under the upwardly directed stress to which it is subjected by the clamp and 65 this is accomplished by making the curb of upwardly tapering cross section, though, as will be understood, such upwardly tapered curb surfaces may be provided only at those portions of the curb in registration with the clamps and the remainder of the curb be made of any other shape 70 desired.

Furthermore, the engaging of the clamps with the heads at a low elevation presents the further advantage, not only of economy of construction 75

but also of avoiding objectionable projections at such elevations as might injure animals in the stalls.

It may be further stated that the openings in the faces of the curb may be provided either as separate openings formed therein in the building of the curb or by chipping them in the faces of the curb, or may be provided as continuous grooves formed either in the casting of the curb or subsequent thereto.

While I have illustrated and described certain particular constructions constituting embodiments of my invention, I do not wish to be understood as intending to limit it thereto as the same may be variously modified and altered and the invention embodied in other forms of structures, without departing from the spirit of my invention.

What I claim as new, and desire to secure by Letters Patent, is:

1. The combination in barn equipment of stall frame members of a series of stalls, a curb presenting upwardly converging face portions, and frame-supporting devices comprising clamps operatively engaging said members and having spaced apart downwardly diverging portions, said clamps straddling said curb with their diverging portions extending down said converging face portions and means whereby the clamps are caused, in clamping, to exert compression stresses against the curb having substantially vertical and horizontal components.

2. The combination in barn equipment of stall frame members of a series of stalls, a curb having downwardly facing portions at its opposite faces, and frame-supporting devices comprising clamps operatively engaging said members and having spaced apart downwardly diverging portions with inwardly extending projections, said clamps at their said downwardly diverging portions extending down said curb and at their projections extending beneath said downwardly facing portions and means whereby the clamps are caused, in clamping, to move inwardly at said portions and bear upwardly at their projections against the upper walls of said downwardly facing portions, and thereby exert compression stresses against the curb having substantially vertical and horizontal components.

3. The combination in barn equipment of stall frame members of a series of stalls, a curb, and frame-supporting devices comprising clamps operatively engaging said members and straddling the curb and means whereby the clamps are caused, in clamping, to exert compression stresses against the curb having substantially vertical and horizontal components comprising a single operating element for each clamp and operatively engaging the clamp and said stall frame member.

4. The combination in barn equipment of stall frame members of a series of stalls, a curb having downwardly facing portions at its opposite sides, and frame-supporting devices comprising clamps operatively engaging said members and having depending portions at opposite faces of the curb provided with inwardly extending projections which extend beneath said downwardly facing portions; said depending portions of said clamps being adapted for movement inwardly toward the curb and means operative to cause said depending portions of the clamps to move toward the curb and upwardly and thereby clamp the curb vertically and horizontally.

5. The combination in barn equipment of stall frame members of a series of stalls, a curb hav-

ing downwardly facing portions at its opposite sides, and frame-supporting devices comprising clamps operatively engaging said members and having depending portions at opposite faces of the curb provided with inwardly extending projections which extend beneath said downwardly facing portions; said depending portions of said clamps being adapted for movement inwardly toward the curb and means engaging said clamps between the areas of contact of the projections with said downwardly facing portions, and operating to exert upward force on said clamps whereby said depending portions move toward the curb and upwardly and clamp the curb vertically and horizontally.

6. The combination in barn equipment of stall frame members of a series of stalls, a curb having downwardly facing portions at its opposite sides, and frame-supporting devices comprising clamps operatively engaging said members and having depending portions at opposite faces of the curb provided with inwardly extending projections which extend beneath said downwardly facing portions; said depending portions of said clamps being adapted for movement inwardly toward the curb and a single operating element for each clamp operative to cause the depending portions of the clamp to move toward the curb and upwardly and thereby clamp the curb vertically and horizontally.

7. The combination in barn equipment of stall frame members of a series of stalls, a curb having downwardly facing portions at its opposite sides, and frame-supporting devices comprising clamps operatively engaging said members and having depending portions at opposite faces of the curb provided with inwardly extending projections which extend beneath said downwardly facing portions; said depending portions of said clamps being adapted for movement inwardly toward the curb and a single operating element for each clamp engaging the clamp between the areas of contact of the projections with the upper walls of said downwardly facing portions and operating to exert upward force on said clamp whereby said depending portions move toward the curb and upwardly and thereby clamp the curb vertically and horizontally.

8. The combination in barn equipment of stall frame members of a series of stalls, a curb having downwardly facing portions at its opposite sides, and frame-supporting devices comprising clamps each formed of separate members operatively engaging said stall frame members and located at opposite sides of the curb and having projections which extend beneath said downwardly facing portions, and means operative to exert upward force against said clamp members and to clamp the curb vertically and horizontally comprising an operating element engaging one of said clamp members.

9. The combination in barn equipment of stall frame members of a series of stalls, a curb having downwardly facing portions at its opposite sides, and frame-supporting devices comprising clamps each formed of separate members disposed in intersecting relation and operatively engaging said stall frame members, the lower portions of said clamp members being located at opposite sides of the curb and having projections which extend beneath said downwardly facing portions, and means engaging one of said clamp members operative to exert upward force against said clamp member and through the engagement of the other of said clamp members with the stall frame mem-

- ber, to exert upward force against the other of said clamp-members.
10. The combination in barn equipment of stall frame members of a series of stalls, a curb, and frame-supporting devices comprising clamps operatively engaging said members and straddling the curb and means engaging lower portions of said clamps and adjustable relative thereto in converging planes and bearing against said curb and operating to cause the clamps, in clamping, to exert compression stresses against the curb having substantially vertical and horizontal components.
11. The combination in barn equipment of stall frame members of a series of stalls, a curb, and frame supporting devices comprising clamps operatively engaging said members and presenting depending portions located at opposite sides of the curb and movable relative to the curb and devices adjustable on said depending portions and disposed in upwardly and inwardly inclined position and engaging the curb at their inner upper ends and operating to cause the clamps, in clamping, to exert compression stresses against the curb having substantially vertical and horizontal components.
12. The combination in barn equipment of stall frame members of a series of stalls provided with lateral projections, a curb, and frame-supporting devices comprising clamps straddling said projections and the curb and means for tightening the clamps.
13. The combination in barn equipment of stall frame members of a series of stalls provided with lateral projections, a curb, and frame-supporting devices comprising clamps straddling said projections and the curb and set screws for tightening said clamps engaging said clamps and said projections.
14. The combination in barn equipment of stall frame members of a series of stalls comprising spaced-apart uprights provided with lateral projections, a curb, bars extending along the curb between adjacent ones of said uprights, and frame-supporting devices comprising clamps straddling said projections, bars and curb and means for tightening said clamps.
15. The combination in barn equipment of stall frame members of a series of stalls comprising spaced-apart uprights provided with lateral projections, a curb, bars extending along the curb between adjacent ones of said uprights, the ends of said bars and said projections overlapping, and frame-supporting devices comprising clamps straddling said projections, bars and curb and means for tightening said clamps.
16. The combination in barn equipment of stall frame members of a series of stalls comprising spaced-apart uprights provided with lateral projections, a curb, bars extending along the curb between adjacent ones of said uprights, the ends of said bars and said projections overlapping, and frame-supporting devices comprising clamps straddling said projections, bars and curb and set screws engaging said clamps and clamping said projections and bars to the curb.
17. The combination in barn equipment of stall frame members of a series of stalls, a curb, and frame-supporting devices comprising clamps operatively engaging said members and straddling the curb and means for tightening the clamps against the curb comprising elements operative to apply primary clamping force to the clamps along converging planes with resultant compression stresses against the curb having substantially vertical and horizontal components.
18. The combination in barn equipment of stall frame members of a series of stalls, a curb, and frame-supporting devices comprising clamps operatively engaging said members and straddling the curb and means for tightening the clamps against the curb comprising elements operative to apply primary clamping forces to the clamps along converging planes, the clamps exerting downward compression forces against the curb at its upper portion, with resultant substantially vertical and horizontal components at points of contact between the curb and the straddling portions of the clamps.

ROBERT G. FERRIS.
